UNITED STATES PATENT OFFICE

DAVID BLOOM, OF BERKELEY, CALIFORNIA

CONTAINER

Application filed December 3, 1928. Serial No. 323,303.

My invention relates to containers and is especially concerned with containers of the type disclosed in my previous patent, Number 1,459,277 issued June 19, 1923, and entitled "Closures for containers". In containers of this type, in which a receptacle is provided and is equipped with a closure embedded in a sealing substance such as paraffin, it is sometimes difficult to ensure that the paraffin will properly embed and secure the closure and receptacle together. And it is also sometimes difficult to remove the closure when it is desired to gain access to the contents of the container.

It is therefore an object of my invention to provide a container in which the sealing material is properly disposed with respect to the receptacle and the closure.

Another object of my invention is to provide means for facilitating the opening of such containers.

An additional object is to improve in general containers of this type.

The foregoing and other objects are attained in the embodiment of the invention shown in the drawings, in which

Figure 1 is a plan of a container constructed in accordance with my invention.

Figure 2 is a transverse section on the line 2—2 of Figure 1.

Figure 3 is likewise a transverse section of a portion of my container, the closure being shown in dislodged position.

Figure 4 is a partial side elevation of a slightly modified form of the container of my invention.

Figure 5 shows in cross section a container constructed of earthenware or glassware.

In its preferred form, the container of my invention preferably includes a shouldered receptacle having a mouth provided with a closure which is embedded in a sealing substance adhering to both sides of the closure as well as to the interior of the receptacle and which is adapted to be dislodged from closed position upon flexure of a portion of the edge of the receptacle.

As disclosed in the drawings, I preferably provide a receptacle 6 having upwardly flaring sides terminating in a mouth 7. With

the type shown in Figure 2, the receptacle is conveniently made of impregnated paper disposed in a suitable form and shaped at its upper end to provide a shoulder 8 having an upwardly flaring contour. To provide a closure for the mouth of the receptacle, I position a disc 9 across the mouth of the container and preferably locate it adjacent the shoulder 8. The disc is conveniently made of paper or other similar material and is perforated, as at 11, well within the confines of the disc. After the substance 12 to be packed has been placed in the container, the closing disc 9 is suitably positioned and a sealing material such as melted paraffin 13 is poured upon the disc 9 and flows thru the perforations 11 to embed the disc completely.

In order to provide an outlet for air which might otherwise remain entrapped, in addition to the perforations 11 I preferably provide perforations 14 on the periphery of the disc so that the disc may be termed notched. These perforations lying at the edge provide an exit for the air within the container and permit the melted sealing substance to adhere not only to the disc but also to the interior walls of the receptacle. The fact that the walls of the shoulder 8 are upwardly flaring permits the sealing substance to become interposed between them and the disc and precludes the possibility of any air becoming entrapped therebetween.

In order to afford a convenient means for opening the container after it has once been sealed as described above, I preferably mark the upper edge 15 of the receptacle with bounding lines 16 defining limited portions thereof. The marks may be simply imprinted upon the material of the receptacle or they can be perforations or weakened portions extending partially therethru. Furthermore, I turn the material of the receptacle upon itself to afford an inturned edge 17 which not only reinforces the mouth of the receptacle but provides what is in effect a lever extending below the closure 9. When I desire to open the sealed container of my invention, I preferably flex one of the marked portions between the lines 16 either after additionally weakening it by a cut along the

lines or, if the perforations are sufficiently deep, by simply tearing the material along the marks and deforming the upper edge 15 outwardly. This results in the inturned

5 portion 17 moving upwardly against the lower side of the closure 9, and dislodging it from sealed position, as is indicated in Figure 3. In this fashion there is provided a very simple and effective way for opening an 10 otherwise tightly sealed container.

In Figure 4 is disclosed a slight modification of the upper edge of a container or receptacle 21 which is contoured with a scalloped or irregular periphery 22 with the peaks of 15 the scallops intermediate the marks or perforations 23. In this form of the device, manual flexure of the upper edge is facilitated and opening of the receptacle is consequently made easier.

20 In Figure 5 is disclosed an earthenware or glassware receptacle 26 having a shoulder 27 formed integrally therewith, the contour of the shoulder being defined by an upwardly flaring surface. Substantially seated upon 25 the shoulder is a closure disc 28 embedded in a sealing substance 29 such as paraffin which, due to the configuration of the shoulder 27, is easily enabled to flow between the lower face of the closure 28 and the flaring surface 30 of the shoulder 27 and not only provides a firm bond therebetween but also insures that any air which might otherwise be entrapped is totally displaced through marginal perforations 31 in the disc.

35 It is to be understood that I do not limit myself to the form of the container shown and described herein, as the invention, as set forth in the following claims may be embodied in a plurality of forms.

40 I claim:

1. A container comprising a receptacle having a mouth, a perforate disc disposed in said mouth, the perforations in said disc being disposed at the periphery thereof, and a 45 sealing substance encompassing said disc.

2. A container comprising a receptacle having a mouth, a peripherally notched disc forming a closure for said mouth, and a sealing substance embedding said closure.

50 3. A container comprising a receptacle having an interior shoulder, a peripherally notched disc substantially seated on said shoulder and forming a closure for said receptacle, and a sealing substance adhering to 55 both sides of said disc and to the interior of said receptacle.

4. A container comprising a receptacle having a mouth, a peripherally notched disc disposed in said mouth, said disc having a 60 plurality of perforations therein, and a sealing substance encompassing said disc.

5. A container comprising a receptacle having a mouth and an inturned flexible edge adjacent said mouth, a closure for said mouth; 65 said closure comprising a peripherally

notched disc having a plurality of perforations therein, and means for confining flexure of said edge to a limited portion thereof to dislodge said closure.

6. A container comprising a receptacle 70 having a mouth, a closure for said mouth, and an inturned edge on said receptacle; said edge being adapted to be fulcrumed adjacent said mouth to serve as a lever for dislodging said closure.

7. A container comprising a receptacle 75 having a mouth, a closure seated in said mouth, and an inturned edge on said receptacle partially underlying said closure; said edge being adapted to be fulcrumed adjacent said mouth to dislodge said closure.

8. A container comprising a receptacle 80 having a mouth, a closure for said mouth, a sealing substance encompassing said closure, and an inturned edge on said receptacle; said edge being adapted to be fulcrumed adjacent said mouth to serve as a lever for dislodging said closure.

In testimony whereof, I have hereunto set 85 my hand.

DAVID BLOOM.
